UNITED STATES PATENT OFFICE.

HENRY ALLEN, OF GAINESVILLE, FLORIDA.

ROLLER GRINDING-MILL

1,207,831.

Specification of Letters Patent. Patented Dec. 12, 1916.

Application filed June 15, 1916. Serial No. 103,753.

To all whom it may concern:

Be it known that I, HENRY ALLEN, a citizen of the United States, residing at Gainesville, in the county of Alachua and State of Florida, have invented a new and useful 5 Roller Grinding-Mill, of which the following is a specification.

The object of the invention is to provide a simple, inexpensive and efficient grinding 10 mill of the roller type wherein the material to be ground is conducted longitudinally or parallel with the axis of the roll or rotary element from one end to the other, so that all portions of the grinding surfaces 15 may be brought into effective operation upon the material, and wherein the grinding elements may be readily removed, replaced, and reground or sharpened, and wherein the coöperative portions of the 20 grinding faces may be relatively adjustable to vary the fineness of the product and the rate of grinding.

Further objects and advantages of the invention will appear in the following description, it being understood that changes in the form, proportions and details of construction within the terms of the claims 25 may be resorted to without departing from the spirit of the invention.

30 In the drawings:—Figure 1 is a vertical sectional view of a mill constructed in accordance with the present invention. Fig. 2 is a sectional view at right angles to the plane of Fig. 1 on the line indicated 2—2 35 of Fig. 1. Fig. 3 is a face view of a baffle. Fig. 4 is a detail view of a section of the rotary grinding element. Fig. 5 is a similar view of a section of the stationary grinding element.

40 The mill essentially consists of a rotor and a stator having coöperative grinding surfaces arranged in a casing consisting in the construction illustrated of a head plate 10 and a tail plate 11, the grain or other 45 material to be ground being introduced through a feed opening 12 in the former by means for example of a hopper 13, while the meal is discharged through an outlet 14 after having passed the length of the 50 grinding elements. Both rotor and stator are of sectional construction on planes transverse to the axis of the former which in the construction illustrated consists of a roll 15 carried by a shaft 17, while the 55 latter consists of a breast or concave 18 suitably supported in the casing. The sec-

tions 19 of the roll are preferably threaded as at 20 upon the shaft, to permit of their removal and replacement or grinding and sharpening, and the serrations on said roll 60 sections are preferably arranged diagonally with reference to the axis of the roll, to afford a feeding action upon the material being ground, said serrations being readily filed or sharpened by any suitable instrument when the sections have been removed from the machine. The breast or concave consists of a series of sections or rings 21, having their inner or grinding surfaces 65 similarly serrated to coöperate with those of the roll sections, and said breast or concave sections or rings are of approximately oval form as shown clearly in Figs. 2 and 5 to provide a feed chamber or passage 22 between the roll and the long diametered portions of said rings and in registration with the feed opening 12. Also a baffle consisting of a plate 23 may be interposed between 70 two of the breast or concave sections, and is provided with an opening 24 approximately fitting the roll in contour, and adapted, by means hereinafter described, for adjustment to vary the extent of obstacle which it offers to the forward feeding movement of the material passing through 75 the mill.

80 In the construction illustrated, the breast or concave sections are pivotally mounted by means of a bolt 25 within the casing, and are engaged at a remote point by a bolt 90 26 fitted at its extremities in slots 27 in the casing or tail plate of the frame, nuts 28 being provided to secure said bolt and hence the sections of the breast or concave 85 at the desired adjustment. The movement 95 of the bolt 26 in the frame slots serves to vary the distance between the grinding portions of the surfaces of the rotary and stationary elements of the device, and to facilitate this adjustment there is provided a 100 strut bar 29, (one for each end of the bolt) engaged at its upper end with the bolt and engaged in turn at its lower end by a set screw 30. By the adjustment of the set screw the strut bar may be moved to either raise 105 or lower the bolt 26 and thereby more or less incline the breast or concave sections, to vary the fineness of the product. The baffle plate is also engaged with the bolt 26 to 110 form a pivot and is slotted as at 31 to receive the bolt 25, so that any desired adjustment of said baffle plate with relation

to the sections of the breast or concave may be effected. Also the sections, or some of the sections of the breast or concave are provided with radial grooves or depressions 5 32 to form air inlets and provide for a circulation.

In operation it will be noted that the material to be ground is introduced at one end of the apparatus and is discharged at 10 the other end, whereby it must in reaching the outlet come within the grinding action of each section of both rotary and stationary grinding elements, thereby insuring uniformity of product while the various adjustments provide for securing not only the 15 desired degree of fineness but also a variation in the rate of grinding, to further add to uniform action upon the material.

What is claimed is:

20 1. A grinding mill having a rotor and a stator constituting coöperative grinding elements, the stator having a substantially oval inner surface facing the grinding surface of the rotor, pivotally mounted eccentrically 25 to the rotor and providing an inclosed feed passage parallel with the axis of the rotor, and means for securing the stator in its adjusted position.

2. A grinding mill having a rotor and a 30 stator constituting coöperative grinding elements, said stator being of sectional construction on planes transverse to the axis of the rotor, and a baffle plate interposed between sections of the stator for obstructing 35 the passage between said elements.

3. A grinding mill having a rotor and a stator constituting coöperative grinding elements, the stator being of sectional construction on planes transverse to the axis 40 of the rotor, a baffle plate interposed between adjacent sections of the stator for obstructing the passage between said elements, and means for securing said baffle

plate in adjusted positions with reference to the sections of the stator.

45

4. A roller grinding mill having a shaft, a roll consisting of a series of sections removably mounted upon said shaft and provided with serrated peripheries, a breast or concave surrounding said roll and consisting of interiorly oval sections arranged in planes at right angles to the axis of the roll and pivotally mounted for adjustment, said breast or concave sections having serrated inner grinding faces, and means for securing 50 said sections of the breast or concave in adjusted position.

55

5. A roller grinding mill having coöperating grinding elements consisting of a roll and a breast or concave, said breast or concave consisting of a series of oval sections arranged in planes transverse to the axis of the roll and surrounding the same to form a feed chamber or passage parallel with the axis of the roll, and means for feeding and 60 delivering the material respectively at opposite ends of the roll.

65

6. A roller grinding mill having coöperative grinding elements consisting of a roll and a breast or concave, the latter comprising a series of oval sections disposed in planes transverse to the axis of the roll, means for pivoting said sections of the breast or concave, a bolt engaging said sections at a point remote from the pivot, 70 strut bars engaging said bolt, set screws for adjusting the strut bars, and means for securing the parts in their adjusted positions.

75

In testimony that I claim the foregoing as my own, I have hereto affixed my signature in the presence of two witnesses.

80

HENRY ALLEN.
